CLAIM

The ornamental design for an accessory for handheld device, as shown and described.

DESCRIPTION

FIG. 1 is a top, front, left side perspective view of an accessory for handheld device, showing our new design; FIG. 2 is a front elevation view thereof; FIG. 3 is a rear elevation view thereof; FIG. 4 is a left side elevation view thereof; FIG. 5 is a right side elevation view thereof; FIG. 6 is a top plan view thereof; FIG. 7 is a bottom plan view thereof; and, FIG. 8 is a top, front, left side perspective view of the accessory for handheld device of FIG. 1, shown in an environment of use.

Dash-dash broken lines illustration portions of the accessory for handheld device that form no part of the claimed design. Dash-dot broken lines depict environmental subject matter and form no part of the claimed design.

1 Claim, 8 Drawing Sheets
